UNITED STATES PATENT OFFICE

FRANCIS C. COPELAND, OF SAN FRANCISCO, CALIFORNIA

DISPENSER AND LIGHTER FOR CIGARETTES AND CIGARS

Application filed November 23, 1927. Serial No. 235,168.

This invention relates to dispensing and lighting mechanism for cigarettes and for cigars.

The object of the invention is to provide a device capable of dispensing and igniting cigarettes or cigars, which device is in form suitable for use on a desk or table and is capable, upon actuation of a single lever or key, of discharging a single cigarette or cigar and thereafter automatically igniting the same.

In the accompanying drawings,

Fig. 1 shows a side elevation of a preferred form of the device, certain parts of the housing being broken away to illustrate the mechanism;

Fig. 2 shows a vertical central sectional view of the device shown in Fig. 1;

Fig. 3 shows a side elevation of a modified form of the device, certain parts of the housing being broken away to illustrate the mechanism enclosed thereby;

Fig. 4 shows a front elevation partly in section, of the device illustrated in Fig. 3.

Referring particularly to the device illustrated in Figs. 1 and 2, it will be seen to comprise a base 10, upon which is a housing 11 having a receptacle 12 in its upper portion to contain a quantity of cigarettes or cigars. The receptacle is preferably provided with a hinged cover 14 at its top. The floor of the receptacle is formed by a forwardly and downwardly inclined or curved plate 15 having a bead or obstruction 16 at its forward end, against which a cigar or cigarette will rest at all times when the receptacle is filled.

In spaced relation with the floor is a feeder plate 17, pivotally mounted at 18. There is a rod or pin 19 on the lower end of this plate, extending through an arcuate slot 20 in one side of the housing and connected to a link 21. This link is connected at its other end to a pin 22, which passes through an arcuate slot 23 and supports a kicker plate 24, disposed below the floor of the receptacle. This kicker plate when actuated is adapted to project through a slot 25 in the floor plate and kick the lowermost cigarette over the bead or obstruction 16. The link 21

is pivotally connected intermediate its ends to a link 26, which in turn is pivoted to a lever 27 fulcrumed at 27^a on the wall of the housing. The lever is actuated by a key 28 which projects through the top of the housing and is adapted to be depressed by the thumb or finger of the operator. The key is normally held in raised position by a spring 29 connected to the side of the housing.

An arm 30 pivoted at 31 on the housing carries an electric contact plate 32 which contacts with a stationary contact 33. The pivoted contact carried member is held out of contact with the stationary member when the key is in raised position, by means of a strap 34 fixed to the link 26 and adapted to rest on top of the pivoted member 30. A suitable spring may be provided to raise the arm 30 when the pressure of the strap 34 is removed, and thereby bring the contact points together. These contacts are electrically connected to a suitable igniting element 35, arranged in the base 10 at one side thereof.

Disposed on the incline and in line with the igniting element are two hook-shaped brackets 36, secured to and extending down from the front edge of the floor plate 15. Thus, when a cigarette is kicked over the bead 16, it falls onto the brackets and is guided on an incline down into contact with the igniting element. In this position of the cigarette, one end resting against the igniting element, the cigarette will be ignited without suction being applied thereto. The housing has a front wall 37 which terminates a short distance below the floor plate 15, which serves to prevent a cigarette being thrown too far forward when the kicker plate strikes the same. There is an inclined plate or deflector 38 above the igniting element, which serves to ignite one end of the cigarette during its fall onto the brackets, which prevents the cigarette from coming into contact with the igniting element except by an endwise, sliding motion, after it is received by the brackets.

In the operation of the device shown in Figs. 1 and 2 with a quantity of cigarettes in the receptacle, the lowermost cigarette will be held against rolling off by the bead 16.

The other cigarettes will be held back by coming in contact with the lowermost cigarette and with the lower edge of the feeder plate 17. When the key is depressed, the kicker 5 plate is raised to kick the lowermost cigarette off the bead 16, and simultaneously the feeder plate is swung inwardly, carrying with it the entire batch of cigarettes. When the key is released, the kicker plate is retracted and the 10 feeder plate returns to its forward position. In this latter position there is sufficient clearance between the lower edge of the feeder plate and the floor plate to permit a cigarette to pass, and one is thereupon advanced to the 15 point where it is stopped by the bead 16. The cigarette adjacent the lowermost one, owing to the curvature or incline of the floor plate, is in a raised position where it will be in the path of the feeder plate as the latter swings 20 inwardly on the next actuation; but said feeder plate will at all times clear the lowermost cigarette. This feeder plate serves to insure delivery of a single cigarette in each actuation, and prevents clogging of the 25 ejector mechanism, and by its movement carries with it the entire batch of cigarettes and has the effect of lining them up properly in case they should be thrown into the receptacle in a haphazard arrangement.

30 When the key is depressed the electric contacts are automatically closed and the key should be held depressed sufficiently long to enable the igniting element to light the cigarette which has been ejected.

35 The device shown in Figs. 3 and 4, so far as the feeding or ejector mechanism is concerned, is identical with the one shown in Figs. 1 and 2. In place of the depressable key 28, I show a lever 39 pivotally mounted near 40 the bottom of the housing at one side thereof. This lever is connected at its inner end to a link 40, and the link at its upper end is connected to the pin 19 on the feeder plate. The said feeder plate and kicker plates are connected together for joint operation by the 45 link 21, as in Fig. 1. A spring 41 connected between the link 40 and lever 39 serves to maintain the forward end of the lever in raised position, and the said link at the lower 50 end of the arcuate slot 20.

Various changes in the construction and arrangement of the several parts of the device herein disclosed may be employed without departing from the spirit of my invention, as 55 expressed in the appended claim.

Having thus described my invention, what I claim as new and desire to secure by Letters Patent is:

A cigarette dispenser comprising a receptacle for a quantity of cigarettes, having an inclined curved floor, said receptacle being formed with a discharge opening immediately adjacent the lower edge of the floor through which a single cigarette may pass, a movable 60 ejector adapted to dislodge the lowermost

cigarette, a pivotally mounted plate adjacent the discharge opening movable in unison with the ejector to positively retain all of the remaining cigarettes in the receptacle during ejecting operation, the curved floor 70 positioning the cigarettes so as to be engaged by the pivotally mounted plate.
